UNITED STATES PATENT OFFICE.

WILLIAM T. SHEPERDSON, OF PAXTON, MASSACHUSETTS; JOHN WILLIAM SHEPERDSON EXECUTOR OF SAID WILLIAM T. SHEPERDSON, DECEASED.

HORSESHOE AND CALK.

Application filed October 28, 1926. Serial No. 144,840.

The principal objects of this invention are to provide an improved form of calk in which the wearing of the calk will not really reduce its sharpness, and at the same time 5 avoid the presence of pockets which can be filled up with dirt or the like and perhaps be frozen in position; also to provide replaceable calks so constructed that they will not turn or fall out, due to the special shape 10 of the shank; and to provide other improvements in a replaceable drive calk and rolled horseshoe to which they are applied.

Reference is to be had to the accompanying drawings in which

15 Fig. 1 is a bottom plan view of a horseshoe with calks in place constructed in accordance with this invention;

Fig. 2 is an edge view of the same;

Fig. 3 is a top plan;

20 Fig. 4 is an enlarged sectional view on the line 4—4 of Fig. 1;

Fig. 5 is a side view of one of the heel calks;

25 Fig. 6 is a central transverse sectional view of the same showing the shank however in elevation;

Fig. 7 is an elevation of the toe calk, and Fig. 8 is a bottom plan view of one of the calks.

30 Referring first to the shoe in which there are some features of importance, it may be stated that this shoe 10 is produced by rolling instead of drop forging, and is thinned along an area 11 on the under side for lightness, and also slanted off on the top throughout an area 12 on the inner side partly for lightness. This shoe is provided, of course, with the usual nail-holes 13 and with two perforations 14 for the heel calks, these perforations being circular with opposite flat sides. A similar perforation 15 is provided for the toe calk. This shoe is creased at 16. To lighten the shoe it is rolled thinner between the toe and heels at 11 as specified, 35 and has a special groove 12 as shown. In the inner side of the shoe there is a groove 17 extending around the interior and of special form for the purpose of lightening the shoe. This reduces the width of the shoe on the bottom but not on the top as the groove is located at the bottom.

40 It will be understood that the calks are made replaceable and that different calks may be used for summer and winter wear.

The calk illustrated is for winter use as that 55 will disclose the invention sufficiently.

The toe calks 18 and the heel calks 19 have similar characteristics, but, of course, the toe calk is of arcuate form while the heel calks may be straight. In both cases each 60 calk is provided with a central shank 20 which is of a general circular shape but having flattened sides 21 opposite each other to fit in the perforations 14 and 15. The flat sides have a greater taper than the two half 65 round surfaces of the shank. The flat surfaces of the shank drive into the tapered hole 14 or 15 of the shoe like a wedge and the round part with the smaller taper helps to tighten the calk. This is an important feature, 70 as the calk is held in place firmly after once being applied, and on account of the flat sides it will not twist. The shanks of the summer calks are also made in the same way, and the summer calks are replaceable like 75 the winter calks. These calks are also reversible in case the outside of the calk should wear down faster than the inside, or a calk could be placed on the other foot.

The calk itself, in each instance, is formed 80 with a plain web 23 throughout the center, curved in the case of the toe calk, to correspond with the shape of the calk as a whole. This web is of substantially uniform thickness from the base of the calk to the tip, 85 so that as it wears down it will retain the same thickness all the time and will not get thicker and thicker and have a blunt operating edge as it grows shorter. Such a shape by itself would be impractical because it 90 would be easily broken or bent.

For the purpose of strengthening it, I provide each calk at its two ends with a transverse strengthening flange 24. These strengthening flanges are triangular in shape 95 extending from the base to the tip of the web 23 and of a thickness as great as the thickness of the web, or greater, so that they constitute struts to hold the tip of the web in its original position at all times and protect the web 23 from getting bent or broken. The surfaces 25 by which the edges of the flanges 24 are connected with the web 23 are all slanting in both directions so as to avoid any parallel surfaces that would hold 100 dirt and mud. On the other hand these surfaces are of such shape as to permit anything that once collects in them to 105

drop away, with the help of the jar-
ring to which the horseshoe is put when
in use. Therefore these cavities do not fill
up in practice, and the mud which they tem-
porarily collect will not have time to freeze
5 therein.

In the case of the toe calk, I provide it
with a shoulder 26 about a 16th of an inch
deep and located at each end to furnish
10 space enough at the ends of the blade to
receive an extractor and permit of its being
removed under all conditions.

It will be seen that this invention involves
a new shape of blade on a drive calk with
15 strengthening walls at its ends, also a new
shape of shank with flat sides and half-
round sides. The flat sides have a greater
taper and the half-round sides a smaller ta-
per thus helping to hold the calk in tight,
20 and the shoe having holes punched in it to
correspond to the specific shape of the shank
mentioned.

Although I have illustrated and described
only a single form of the invention I am
25 aware of the fact that changes can be made
therein by any person skilled in the art
without departing from the scope of the in-
vention as expressed in the claims. There-
fore I do not wish to be limited to the exact
29 form shown, but what I do claim is:—

1. As an article of manufacture, a replace-
able horseshoe calk having a central longi-
tudinal plain web of substantially uniform

thickness, and having transverse triangular
end walls connecting the ends of the web to 35
the base for strengthening the web, the sur-
faces connecting the interior surfaces of the
web and end walls all diverging from each
other from the center outwardly, whereby
the centers of the end walls at their bases 40
are thicker than their edges, and said calk
having positive means for preventing it from
turning.

2. As an article of manufacture, a replace-
able horseshoe calk having a central longi- 45
tudinal web of uniform thickness and having
end walls connecting the end of the web
to the base for strengthening the web, said
calk having a shank with two opposite flat
sides and two opposite arcuate sides, the 50
flat sides having a larger taper than the
arcuate sides.

3. The combination with a horseshoe having
a perforation with two opposite flat sides
having a comparatively large taper and two 55
opposite rounded sides having a smaller
taper, of a calk having a shank with opposite
flattened sides and opposite rounded sides,
having tapers like the perforations, whereby
the flat sides of the shank can be driven 60
into the perforation and they will hold it like
a wedge, and the rounded sides with a small-
er taper will tighten the calk.

In testimony whereof I have hereunto af-
fixed my signature.

WILLIAM T. SHEPERDSON.
